ROLLER SKATE STRUCTURE

Stanley W. Blumm, Marathon, N. Y.

Application July 26, 1945, Serial No. 607,183

7 Claims. (Cl. 280—7.13)

1

The present improvements relate to a compact, all-metal skate of simple design particularly intended for juvenile use, and one which may readily be converted into either an ice skate or a roller skate and be profitably marketed at a moderate retail price. The novel structural features herein embodied afford a rigid cross-sectionally bifurcated runner blade for ice skating and detachably centered in the mouthed crotch thereof, is a unitary roller mounting chassis of the underslung type. The stabilized disposition of these components is such as to provide for a sturdy roller skate assembly that shall present a trim appearance and require comparatively few principal parts adapted to be economically stamped from sheet metal on a rapid productive basis. When detached, my unused chassis may be independently stowed without chassis dismemberment.

The object of my invention is to devise a refined convertible skate of the indicated character in which a cross-sectionally socketed runner blade may be demountably seated upon a unitary roller-mounting chassis and permitting the bodily detachment of such chassis as an assembled unit. Embodied herein are also structural refinements pertinent to a roller skate assembly of the non-separable chassis type.

Reference is had to the accompanying one sheet of drawings which exemplifies a preferred embodiment of my skate, and in which:

Fig. 1 represents a top view of such convertible skate assembly; and Fig. 2 is an elevational side view thereof with my chassis attached for roller skating purposes.

Fig. 3 is cross-sectionally taken along 3—3 of Fig. 1.

Fig. 4 shows a front elevational view of Fig. 2; and Fig. 5 is a cross-section taken along 5—5 of Fig. 3.

Referring more explicitly to these disclosures, the ice skate component thereof may comprise a semitubular, cross-sectionally dished or socketed runner 10 of sheet metal shaped to provide for divergent double blades 11 and 12 that respectively provide for the sharpened runner edges 11A and 12A as indicated in Fig. 5. The apex or crown region of such U-shaped runner is preferably given an arcuate profile 13 while the toe or forward ends of said cutters may be curved upwardly to terminate into a rounded nose 26. The rear end region of the runner crown may be slotted at 15 and have a heel plate 16 that is propped by the cup 25 and adjustably erected along said crown by the clamping bolt

or the like coupling means 17. The upstanding ear 18 of such plate may be apertured at 19 for the reception of a conventional tie strap (not shown).

Intermediate its ends, the runner 10 may be equipped with a substantially flat sole plate 20 as mounted upon the toe cup 21 having its base fixedly riveted to the runner at 22. Said sole plate may be provided with one or more sunken strap receiving lugs such as 23 or with equivalent shoe engaging means. The forward end of such sole plate may have a stabilizing strut 24 struck therefrom and cleated to the runner crown as in Fig. 3. Both of my sole and heel plates are purposely elevated above the level of the runner socket and arranged to present a substantially flat foot rest devoid of upstanding ridges.

The foregoing description is directed to the several structural elements that collectively constitute the ice skate component of my assembly and as such may be independently utilized in a conventional manner. In order to provide for a multipurpose skate, my improved chassis has been adapted to be securely coupled to the aforesaid component. To this end, I provide for a stamped sheet metal understructure or unitary roller chassis 30 having an inverted troughlike cross-sectional profile. Such framework preferably comprises a stepped region defined by the 20 parallelly aligned flat flank flanges 31 and 32 which may be integrally spanned by the saddle ridge 33 extending longitudinally of the chassis length as shown. Said centralized ridge may be shaped to snugly nest interiorly beneath the 30 socketed runner in the underslung fashion cross-sectionally depicted in Fig. 5. As will be obvious, the dished runner 10 and the nested saddle ridge 33 may in certain instances be integrally affixed to support the heel and sole plates 16 and 20 40 thereon.

The rear ridge region may be slotted in registry with the runner slot 15, the bolt 17 being kept sufficiently long to clampingly enter therethrough. Similar supplementary bolts or dowels such as 17A and 17B serve to additionally retain the saddle ridge 33 against displacement when assembled in place as a convertible skate. All bolt heads are rendered accessible to have an ordinary screw driver or its equivalent applied thereto without need of other implements, the square bolt nuts being prevented from turning within the ridge confines. The seated double blade 10 is purposely disposed to leave a protective clearance 55 gap 34 between the straddling sharpened edges

11 and 12 and their respective underlying flank flanges 31 and 32.

Each outer edge of such flank flanges may carry a single depending skirt flange 35 or 36 that preferably extend in parallelism with the runner length and render the trough shaped framework intrinsically rigid under a wide tread roller loading. Each such skirt flange may have its blanked free edge shaped to provide for a pair of return-bend axle retaining clips 37 and 38 that may be integrally appended to said free edge and alignedly apertured with respect to their mated clips 37' and 38' to respectively mount the axles 39 or 40 therethrough. A pinching action on part of said clips may serve to stall these axles against unwanted rotation. Each overhanging axle end may journal a bushed roller such as 41 or 42, preferably stamped from cupped sheet metal parts and secured against axial movement by cotter means such as 43.

In order to provide for adequate lateral skate stability, the overall roller tread width is preferably kept substantially equal to that of the toe plate 20. Such desirable characteristic is herein attained by stepping out the respective flank flanges 31 and 32 as shown.

As a further refinement, the toe end of my chassis may be provided with an upturned shroud guard 44 of which the free bib region 47 may supportingly underlie the forwardly projecting toe plate 20 as shown. Such integral guard bib may be notched at 45 to clear the strut 24. The lower guard region may be warped into a continuation of the ridge 33 and may have its upper portion decoratively perforated at 46 or otherwise embellished.

It is emphasized that a loosening of the several clamping bolts 17 bodily releases my unitary chassis along a severable parting surface extending between the nested ridge 33 and the socketed runner 10. This simple expedient operatively exposes the double runners 11 and 12 for use as an ice skate. It will be apparent that the guard feature 44 primarily serves as a bumper agency to protect the user's shoe tip against scuffing when inadvertently skating into an abutment and to impart a trim appearance to the roller skate assembly.

The foregoing preferred exemplification will, it is believed, make evident to those skilled in this art, further advantages inherent in my skate improvements, it being understood that the same underlying principles may likewise be applied to other similar structures, all without departing from the spirit and scope of my invention, heretofore described and more particularly characterized in the appended claims.

I claim:

1. A convertible ice and roller skate assembly embodying mated components of which one such comprises a unitary chassis provided with a pair of laterally spaced roller carrying axles that are bridged by a saddle ridge member, and the other component comprises a semitubular runner mounting a heel and a sole plate thereon and further includes bifurcated parallel blade edges lying wholly above the respective axle centers and between which said runner is longitudinally socketed to nest said ridge therein when assembled in superimposed relationship, and means for severably coupling said nested components.

2. A convertible ice and roller skate assembly embodying superimposed components that are severably united along a parting surface by coupling means, one such component comprising a

unitary chassis provided with a pair of laterally spaced roller carrying axles, a sheet metal saddle member mounted crosswise above the axle centers and having a U-shaped contour of which its rounded crown is disposed upwardly, and the other component comprises a longitudinally socketed runner having a sole plate together with a heel plate erected upwardly beyond the socket confines, said socket being shaped to straddlingly seat a portion of said ridge when borne thereon.

3. A convertible ice and roller skate assembly embodying mated components of which one such comprises a chassis having a framework provided with a pair of laterally spaced roller carrying axles that are bridged by a saddle ridge member having a downwardly divergent cross-sectional U-shaped profile of which the outer longitudinal ridge edges respectively terminate in opposed flank flanges, and the other component comprises a runner mounting a sole plate and a heel plate thereon and provided with bifurcated blade edges providing for a socket therebetween adapted to seat a portion of said ridge when said blade is straddlingly superimposed thereon and which blade edges are respectively kept protectively spaced from a next adjacent flank flange, and means for severably coupling said components in such superimposed association.

4. A convertible ice and roller skate assembly embodying mated components of which one such comprises an elongated chassis frame work having an inverted cross-sectionally troughlike profile shaped from sheet metal to provide complementary flank flanges and an interposed longitudinal saddle ridge, the respective outer edges of said flanges each being provided with a depending skirt flange that respectively mount roller carrying axle means beneath the level of said ridge, and the other component comprises a socketed runner that uphold a sole plate and a heel plate and which runner socket demountably seats when borne upon a portion of said ridge, and means of severably coupling such components in superimposed association.

5. A roller skate assembly comprising a stamped elongated sheet metal chassis framework having an inverted cross-sectionally trough-like profile shaped to provide for complementary longitudinal flank flanges and an interposed saddle ridge, the respective outer flank flange edges each carrying a depending skirt flange of which the respective lower edges are blanked and shaped to provide for a return bend clip, said clips being respectively apertured in registry and having a roller carrying axle entered therethrough, and a sole plate and a heel plate superimposed upon said saddle ridge.

6. A convertible ice and roller skate assembly embodying superimposed components that are severably united along a parting surface by coupling means, one such component comprising a unitary chassis equipped with a pair of laterally spaced roller carrying axles that are bridged by a sheet metal framework including a cross-sectionally U-shaped saddle ridge of which the forward end region is upturned to constitute a shroud guard having a bib portion that is rearwardly directed in an overlying relation to said ridge, and the other component comprises a longitudinally socketed runner that demountably seats upon a portion of said ridge and has the forward runner end region interposed between said bib portion and ridge.

7. A roller skate assembly provided with mated roller carrying axles that are laterally spaced, a

unitary sheet metal framework spanning said axles and having a troughlike cross-sectional shape comprising a pair of aligned interspaced flat flank flanges together with a saddle ridge that bridges the flange interspace and which flank flanges each carry a skirt flange arranged to mount said pair of axles therethrough, the forward end region of said ridge being upturned to

constitute a shroud guard including a bib portion that extends rearwardly over said ridge, and a sole plate and a heel plate borne by said saddle ridge, the forward region of said sole plate being disposed to overlap such rearwardly extending bib portion.

STANLEY W. BLUMM.
